US00D930386S

(12) **United States Design Patent** (10) Patent No.: **US D930,386 S**
(45) Date of Patent: **** Sep. 14, 2021**

(54) **DISPENSER**

(71) Applicant: **CASCADES CANADA ULC**,
Montreal (CA)

(72) Inventors: **Manuel Léveillé**, Montreal (CA);
Olivier Patry, Montreal (CA); **Nathalie**
Comeau, Candiac (CA)

(73) Assignee: **CASCADES CANADA ULC**,
Montreal (CA)

(**) Term: **15 Years**

(21) Appl. No.: **29/750,926**

(22) Filed: **Sep. 17, 2020**

Related U.S. Application Data

(62) Division of application No. 29/647,770, filed on May
15, 2018, now Pat. No. Des. 899,807.

(30) **Foreign Application Priority Data**

Feb. 23, 2018 (CA) ..... CA 179936

(51) LOC (13) Cl. **20-02**

(57) **CLAIM**

The ornamental design for a dispenser, as shown and
described.

DESCRIPTION

FIG. 1 is a perspective view of a dispenser;
FIG. 2 is a front elevation view of the dispenser shown in
FIG. 1;

FIG. 3 is a rear elevation view of the dispenser shown in
FIG. 1;

FIG. 4 is a top plan view of the dispenser shown in FIG. 1;
FIG. 5 is a bottom plan view of the dispenser shown in FIG.
1;

FIG. 6 is left-side elevation view of the dispenser shown in
FIG. 1; and,

FIG. 7 is right-side elevation view of the dispenser shown in
FIG. 1.

The broken lines shown in the figures represent portions of
the dispenser that form no part of the claimed design.

1 Claim, 6 Drawing Sheets
